UNITED STATES PATENT OFFICE

152,670

DESIGN FOR A PHONOGRAPH CABINET

Russell E. Brandenburger, Sr., Shelbyville, Ind., assignor to Packard Manufacturing Corporation, Indianapolis, Ind., a corporation

Application July 21, 1947, Serial No. 140,440

Term of patent 7 years

(Cl. D56—4)

To all whom it may concern:

Be it known that I, Russell E. Brandenburger, Sr., a citizen of the United States, residing at Shelbyville, in the county of Shelby and State of Indiana, have invented a new, original, and ornamental Design for a Phonograph Cabinet, of which the following is a specification, reference being had to the accompanying drawing, forming part thereof.

In the drawing, Fig. 1 is a front perspective view of a phonograph cabinet, showing my new design; Fig. 2 is a side elevational view; and Fig. 3 is a top plan view thereof.

I claim:

The ornamental design for a phonograph cabinet, as shown.

RUSSELL E. BRANDENBURGER, SR.
